METHOD OF MAKING SCREENS FOR
PRINTING OF TEXTILES, ETC.

Louis Martin, New York, N. Y.

Application October 2, 1937, Serial No. 166,913

7 Claims. (Cl. 101—401.1)

This invention relates to the art of printing on textiles and the like, and more particularly to a method or process for producing a printing screen used in this art.

6 The following disclosure will deal with the printing of textiles and it will be readily apparent that the invention may be efficiently employed in other fields.

7 The usual method of producing a printed textile 10 is as follows:

A design is first drawn by an artist on any medium such as paper. The repeat motif of this design is then traced upon a silk screen or the like, said screen being mounted in a frame. The motif 15 being encompassed by straight parallel lines, is traced unit by unit upon the screen until its entire surface is covered by the repeats of the design. Those portions of the design which are not to be printed (as for instance background portions) are 20 covered by an impervious coating, as for instance oil paint. The screen is now positioned over a piece of fabric, and coloring matter applied to the fabric through the interstices of the screen, the imperviously coated portions, of course, preventing the coloring matter from reaching the fabric 25 except through the uncoated interstices.

It is obvious from the above that the manner of applying the design to the screen is quite arduous, expensive, and inaccurate, inasmuch as each motif 30 is separately traced.

The present invention seeks to provide a less expensive method for applying the design to the screen and one which is quite accurate so that all the repeats on the screen are substantially identical. Also the stilted appearance of the design on the printed fabric which is due to the common 35 geometrical application of the motif is obviated by the herein improved manner of rearranging the design motif before its application on the screen.

40 The contemplated method includes first rearranging the geometrical shape of the original motif into an irregularly shaped motif in which the opposite sides of the figure thus formed are identical but irregular so that all tendency towards a stilted appearance is obviated and photographing this rearranged motif upon the screen to 45 provide an accurate means for producing printed fabrics. Particularly where more than one color is to be used, does the present method afford such highly efficient means.

Several preferred manners of practising the invention are illustrated in the accompanying drawings which are described in detail in the following specification.

55 In the drawings:

Fig. 1 is a plan view of a design as provided for reproduction upon the screen and having a two-color motif.

Figs. 2 and 3 are plan views of a stencil, negative, or the like which is made for each color of the design. 5

Fig. 4 shows a portion of the screen upon which one of the negatives has been photographed unit by unit.

Fig. 5 is a view of a piece of fabric which is 10 printed from screens such as shown in Fig. 4.

Fig. 6 is a plan view of another design employing only one color.

Fig. 7 is a plan view of a negative made from the design shown in Fig. 8 but in a manner somewhat 15 different from which the negatives in Figs. 2 and 3 are made.

Fig. 8 is a plan view of still another type of design.

Figs. 9, 10, and 11 are negatives formed for each 20 color of the design shown in Fig. 8.

In practising the herein contemplated method, the original design 15 (Fig. 1) which has portions 16 of one color and portions 17 of another color, is first marked with an irregular line 18 between the top and bottom edges of the design motif, each end of the line being spaced the same from the respective corner of the motif. Similarly, a line 19 is marked between the lateral edges of the design motif. The motif is thus divided into four 25 portions 20, 21, 22, and 23. 30

A transparent plate 24 of Celluloid or the like is then placed over the design 15, the four corners of the design marked thereon, and the lines encompassing the portion 20 traced thereon to provide 35 the area 21^a. The design units 16 are also traced on the plate 24 to provide the portions 16^a.

The plate 24 is then shifted so that the portion 21 of the original design is traced in transposed relation at 21^a on said plate. This is done by positioning the corner markings 25 and 26 upon the corners 27 and 28 of the original design. Here also the design units 16^a are traced. In like manner the design portions 22 and 23 are traced in transposed relation upon the plate 24 at 22^a and 45 23^a.

The motif, formed as above is thus encompassed by irregularly shaped lines instead of the geometrical lines of the original motif, but the area of both is the same. 50

Now, all the portions of the plate outside of the motif are rendered opaque as are also the design units 16^a.

In a similar manner the design motif is reproduced upon another negative plate 28, but in this 55

instance, the design units 17 are reproduced thereon at 17^a.

The negative plate 24 is then placed in a camera and photographed upon a silk screen or the like 5 29 at 30, 30^a, 30^b, etc. This screen is first provided with a sensitized coating which when washed after exposure remains on the screen only at exposed portions in this instance, the background, the unexposed portions 16^b being the resultant images of the design units 16^a.

In a similar manner, another screen is formed by the repeat photographing of the negative plate 28 to provide said screen with the design units 17^a.

The coating which remains on the screen background is normally sufficiently impervious to chemical coloring matter and also quite durable. However, to more surely fix these portions, lacquer may be spread on the screen, said lacquer 20 adhering to said portions but being readily removable from other portions 16^b of the screen by rubbing with cotton waste or the like from the rear thereof.

The screen is now ready for printing. This is 25 done by placing the screen over a length of fabric, placing chemical coloring matter upon the top surface of the screen and applying a squeegee to force said coloring matter through the interstices of the screen at the portions 16^b onto the fabric, the background portions, of course, preventing said 30 coloring matter from reaching those portions of the fabric which they overstand. In this manner the design units 16^c are produced on the fabric (Fig. 5). After this is done, the screen containing the design units 17 is applied to the fabric 35 and the units 17^c reproduced thereon in another color.

From the above it may be seen that tedious tracing upon the screen of the repeat motif is 40 obviated; that said motif because of its irregular shape, eliminates any tendency towards a stilted appearance of the design and also more completely blends the several motifs into a well-balanced and harmonious over-all design; and that the 45 motifs are quite accurately positioned on the screen by the photographic method employed.

In the foregoing disclosure of the herein method, the design motif as formed on the negative provides for "in line" repeating of said motif, i. e., repeat along a horizontal and vertical line. 50 The original design may be transposed, however, so that the repeat may be arranged in an offset or diagonal relation. This is shown in Figs. 6 and 7 wherein the wavy line 19 is similar to that 55 already described but the line 18 is formed as lines 18^a and 18^b offset from each other. Now, when the motif is traced on the negative 31, the design portions 32, 33, 34, and 35 are transposed as the portions 32^a, 33^a, 34^a, and 35^a. When this 60 motif is photographed upon the screen 29, they will assume a diagonal relation with each other. In a like manner, the line 19 may be drawn as two offset portions to obtain diagonal relational positioning in the other direction.

65 The foregoing contemplates a design or designs having spaces through which the wavy lines 18, 19, 18^a and 18^b may be drawn. Some designs may have several colors all in touching relation. Such a design is shown in Fig. 8. This design is 70 a three-color affair requiring three negative plates and three screens for printing the fabric.

As shown, the design has red portions 36, blue portions 37, and stippled portions 38, and no open spaces whatever. But, since each negative plate 75 is provided for its respective color, the wavy line

39 for the red plate may run through the stippled area, the wavy line 40 for the blue plate, through the red area, and the wavy line 41 for the stippled area, through the blue area.

Thus, when transporting the design as before 5 described, the plate 42 is formed for providing the screen for printing the red portions of the design, and the plates 43 and 4 are formed for providing the respective screens for printing the blue and stippled portions thereof. As hereinbefore, 10 the wavy line 19 is used to obviate stilted and geometric repetition of the motif.

It is apparent from the above that the present method lends itself to the printing of variegated and complicated designs in a sure, quick, and 15 economically desirable manner. Skilled persons may deviate from the instant disclosure without, however, departing from the spirit and scope of the invention as claimed. Hence, the prior art rather than the present specific disclosure should 20 form the basis of interpretation of the scope of the invention.

Having thus described my invention, what I claim as new and desire to secure by Letters Patent, is:

1. In the herein-disclosed method, the step of 25 forming a negative plate which comprises placing said plate over an original design, tracing the portion enclosed between two adjacent sides of said design and two irregular lines drawn on 30 the background of said design, and shifting said plate to trace remaining portions of the design in transposed relation to provide a motif having an irregular outline.

2. In the herein-disclosed method, the step of 35 drawing on an original design an irregular line terminating at the top and bottom edges of the design, and drawing another irregular line terminating at the lateral edges of the design, to 40 divide said design into a plurality of areas each having two straight edges and two irregular edges, and transposing said areas upon a transparent plate so the irregular lines form the periphery of the design motif.

3. In the herein-disclosed method, the step of 45 forming a negative plate which comprises dividing an original design into a plurality of areas each having two straight edges and two irregular edges by drawing on said design an irregular line terminating at the top and bottom 50 edges of the design and drawing another irregular line terminating at the lateral edges of the design, then placing said negative plate over the original design, tracing on said plate the portion enclosed between two adjacent sides of said design and two irregular lines drawn on the background of 55 said design, and shifting said plate to trace remaining portions of the design in transposed relation to provide a motif having an irregular outline different from the original outline 60 of the design.

4. In the herein-disclosed method, the step of 65 forming a negative plate which comprises dividing an original design into a plurality of areas each having two straight edges and two irregular 70 edges by drawing on said design an irregular line terminating at the top and bottom edges of the design, and drawing another irregular line terminating at the lateral edges of the design, then placing said negative plate over the original 75 design, tracing on said plate the portion enclosed between two adjacent sides of said design and two irregular lines drawn on the background of said design, and shifting said plate to trace remaining portions of the design in transposed re- 75

5 lation to provide a motif having an irregular outline different from the original outline of the design, and in then rendering opaque the portions of the plate outside the motif and also rendering opaque the design elements within the motif.

10 5. In the herein-disclosed method, the step of forming a negative plate which comprises placing said plate over an original design, tracing the portion enclosed between two adjacent sides of said design and two irregular lines drawn on the background of said design, and shifting said plate to trace remaining portions of the design in transposed relation to provide a motif having an irregular outline, and rendering opaque the portions of the plate outside the motif and also rendering opaque the design units within the motif.

15 6. In the herein-disclosed method, the step of drawing on an original design an irregular line terminating at the top and bottom edges of the design, and drawing another irregular line terminating at the lateral edges of the design, to divide said design into a plurality of areas each having two straight edges and two irregular edges, and transposing said areas upon a transparent plate so the irregular lines form the periphery of the design motif, and rendering

10 opaque the portions of the plate outside the motif and also rendering opaque the design units within the motif.

15 7. In the herein-disclosed method, the step of forming a negative translucent plate from an original multi-colored design which comprises drawing an irregular line on the original design through a color other than that for which a plate is to be made, said line terminating at opposite edges of the design, and drawing another irregular line to intersect the first irregular line and terminating at other opposite edges of the design, thus dividing the original design into a plurality of areas each having two straight edges and two irregular edges, then placing said negative plate over the original design, tracing on said plate the outlines of the desired color enclosed between two adjacent sides of said design and two irregular lines drawn thereon, and shifting said plate to trace remaining portions of the desired color 20 of said design in transposed relation to provide a motif having an irregular outline different from the original outline of the design, and in then rendering opaque the portions of the plate outside the motif and also rendering opaque the 25 design elements within the motif.

LOUIS MARTIN.
